UNITED STATES PATENT OFFICE

2,041,466

STEREOPTICON SLIDE

Samuel M. Gertz, Chicago, Ill., assignor to All American Slide Corporation, Chicago, Ill., a corporation of Illinois

Application December 19, 1935, Serial No. 55,285

4 Claims. (Cl. 88—26)

This invention relates to a type of stereopticon slides on which transparent circular disks, carrying radially disposed markings or data, are adapted to receive a temporary whirling motion, 5 which, with the ending of such rotation, will indicate the winning combination of the markings which are found in aligned relation of a particular marking of each disk, with the single marking on the border of a circular light opening the 10 front wall of the stereopticon slide. The device being more especially intended for use in motion picture exhibition during intervals in such exhibitions in which the withdrawal of a picture film from the projection machine used and the introduction 15 therein of a succeeding picture film, during which intervals a display is given on the picture screen of the markings of the disks and the final result or combination found in register on the stopping of the whirling of the said disks.

20 And this improvement has for its object:

To provide a structural formation and combination of parts and features in a stereopticon slide of the type above referred to, comprising a pair of transparent disks capable of receiving 25 independent whirling impulses from the operator in charge, said disks being arranged in operative relation to the usual transparent circular light passage in the front wall of a stereopticon slide of the present type. The disks and the border 30 of said light opening carrying related data or markings, which, after the whirling or rotation of the disks comes to a stop, a related marking on one disk with a related marking on the other disk found in aligned relation with the single 35 marking at the border of the aforesaid light opening in the front wall of the slide will indicate the winning combination or result at the end of the display, and thereby afford an interesting exhibition of the chance operation of the device, all as 40 will hereinafter more fully appear.

In the accompanying drawing:

Fig. 1 is a front elevation of a stereopticon slide embodying the preferred form of this invention, portions of the device are broken away to disclose 45 portions of the rearwardly arranged members of the device.

Fig. 2 is a horizontal section on line 2—2, Fig. 1.
Fig. 3 is a fragmentary section on line 3—3.

Fig. 1.
50 Like reference numerals indicate like parts in the different views.

In the preferred form of this invention, as shown in the drawing, the marginal frame 1 of the stereopticon slide is of the ordinary rectangular shape, and of a like shape in cross section of

its component rails, with said rails formed midway of their widths with inner tongues 2, the dual function of which is to maintain the forward and rearward transparent plates 3 and 4 in proper spaced relation and provide a central chamber 5 in the slide for the reception of the pair of whirling chance disks now to be described.

Transparent disks 5 and 6 are arranged in the aforesaid central chamber of the slide and adapted for free rotation therein by a journal shaft or 10 spindle 4' which is supported by central orifices in the forward and rearward transparent plates 3, 4, above described. In the drawing, the forward transparent disk 5 carries a plurality of radially disposed symbols or markings, such as to names 15 of a plurality of racing horses, while the rearward disk 6 carries a plurality of circularly arranged numerals in a plane immediately outside the symbols or marking on the forward disk 5 aforesaid.

In coacting relation to the above described markings of the disks 5 and 6, the forward transparent plate 3 of the slide is provided with a stationary marking or line 7, adapted to register with and indicate the winning combination of the 25 symbols and markings of the whirling disks 5 and 6 which may chance to come into register with said marking 7 as said disks come to rest at the ending of their whirling movements, with a resulting very clear display on the picture screen 30 of the winning combination.

With a view to greater clearness in said display, the transparent forward plate or panel 3 of the slide will be provided with a layer or covering 8 of light intercepting material except as to a central and circular portion of the front plate or panel 3 left transparent and in alignment with the disks 5 and 6 aforesaid.

Any usual means capable of imparting a rapid whirling impulse to the transparent disks 5, 6, 40 may be employed without departing from the scope of this part of this improvement. In the preferred construction shown in the drawing, a blast of air is employed as the impelling means with a structural arrangement of parts as follows: 45

Each disk 5, 6, is provided with a marginal metal enclosure 9, which in turn is provided with a plurality of radially disposed blades 10 adapted to receive the impact of a moving body of air, which moving body or blast of air is conducted 50 by bifurcated passages 11 in the frame which have tangential relation to the periphery of the disks 5 and 6 and the radial blades 10 arranged thereon.

The supply or blast of air for the above stated 55

use is under the control of the operator and can be readily provided by a compressible bulb of rubber or the like, the outlet of which has communication with a main passage 13 in the frame 5 1, with said main passage having communication in turn with the bifurcated passages 11, 14 aforesaid.

Having thus fully described my invention, what I claim as new, is:—

- 10 1. A stereopticon slide of the type herein described, comprising a marginal frame formed with a central chamber, means for supporting a journal shaft or spindle centrally in said chamber, a pair of transparent disks mounted on said journal shaft for independent whirling movements, with one of said disks carrying radially arranged symbols or marking adapted for chance registry with one or another of circular plurality of numerals carried on the companion transparent disk on the stoppage of the whirling movements of said disk, a stationary index or pointer carried on the frame or slide for registry with the winning symbol and numeral of the disks, and means for imparting whirling impulses to said disks.
- 15 2. A stereopticon slide as specified in claim 1, wherein the means for effecting whirling movements of the pair of transparent disks comprises a main air supply passage in the frame 20 of the slide ending in bifurcated discharge passages in tangential relation to the peripheries of

said disks, with said main passage being adapted for connection with a source of air pressure.

3. A stereopticon slide of the type herein described, comprising a marginal frame, forward and rearward transparent plates secured within said frame in spaced relation to provide a central chamber, a journal shaft or spindle mounted centrally in said plates, a pair of transparent disks mounted in said journal shaft for independent whirling movements, with one of said disks carrying a plurality of radially arranged symbols or marking adapted for chance registry with one or the other of a plurality of circularly arranged numerals carried by the companion transparent disk on a stoppage of the whirling movements 10 of the disks, a stationary index or pointer carried by the forward transparent plate of the slide for registry with and indicative of the winning combination symbols and markings of said disks, and means for imparting whirling impulses to 15 20 said disks.

4. A stereopticon slide as specified in claim 3, wherein the means for effecting whirling movements of the pair of transparent disks comprises a main air supply passage in the frame of the 25 slide ending in bifurcated discharge passages in tangential relation to the peripheries of said disks, said main passage being adapted to have connection with a source of air pressure.

SAMUEL M. GERTZ.
